[57] CLAIM

The ornamental design for an emergency communications stanchion, as shown and described.

DESCRIPTION

FIG. 1 is a front elevation of the preferred embodiment of the stanchion of our invention;

FIG. 2 is a rear elevation of the stanchion shown in FIG. 1; FIG. 3 is a right side elevation of the stanchion shown in FIG. 1;

FIG. 4 is a left side elevation of the stanchion shown in FIG. 1;

FIG. 5 is a top plan view of the stanchion shown in FIG. 1; and,

FIG. 6 is a bottom plan view of the stanchion shown in FIG. 1.

The broken lines are shown for illustrative purposes only and form no part of the claimed design.
